Inventor

UNITED STATES PATENT OFFICE.

WILLIAM F. MÜLLER, OF NEW YORK, N. Y.

DESIGN FOR CLOCK-FRONT.

Specification forming part of Design No. 6,099, dated September 3, 1872.

To all whom it may concern:

I, WILLIAM F. MÜLLER, of the city of New York, county and State of New York, have invented and produced a new and original Design for Clock-Fronts, of which the following is a specification, reference being had to the accompanying photographic illustration, which gives a front elevation of my design.

This invention relates to a design for a clock-front, the design, graceful in outline, being composed mainly of foliage, shell ornaments, arabesques, and other ornamental figures, as seen in the photograph. The design is further

embellished by a pair of Indian heads, one on each side of the dial-hole *d*, giving the whole a finished appearance.

What I claim as my invention, and desire to secure by Letters Patent, is—

The design for clock-front, as above shown and described.

Signed by me this 22d day of July, 1872.

WILLIAM F. MÜLLER.

In presence of—

J. P. AECKERSBERG,
CHARLES KIETSCHETT.
